CLAIM

The ornamental design for a trash can, as shown and described.

DESCRIPTION

FIG. 1 is a top right perspective view of the trash can showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof; and,

FIG. 8 is a bottom left perspective view thereof.

The broken lines shown in the figures are for the purpose of illustrating portions of the trash can and form no part of the claimed design.
